No 1,539.

J. W. Hayes' Design for Sand-Blower.
Patented July 18, 1863.

Witnesses:

Wm. H. Hayes

Inventor:

J. W. Hayes

Dec. 1539

Jabez W. Hayes, of Newark, N. J.
Letters Patent No. 1539, dated Feb. 18, 1862.

The schedule referred to in these Letters Patent, and making part of the same.

To all whom it may concern:

Be it known that J. J. W. Hayes, of Newark, in the County of Essex and State of New Jersey, have invented or produced a new and original design to be impressed in or stamped upon Sword Blades, and I do hereby declare that the following is a full, clear and exact description of the same, reference being had to the accompanying drawing making a part of this specification, said drawing being a side view of a portion of a sword blade having my design impressed in or stamped upon it.

My design consists of the head or portrait of Washington which is impressed in or stamped on the sword blade near the hilt.

In the accompanying drawing A, represents a portion of the sword blade near the hilt, and B, represents the head or portrait of Washington, which is impressed in or stamped on the smooth or flat part a, of the blade between the tang b, and the longitudinal hollow or groove c.

The head or portrait thus produced has precisely the same appearance as an ordinary line engraving on steel, and in fact is a facsimile of the engraving originally made for the purpose, and forms

an appropriate, chased, neat, and ornamental design, trade mark for sword blade, and one which is durable as it will not, owing to the position in which it is impressed in or stamped on the blade, be subject to wear so as to be rendered indistinct, nor can it be removed by filing or other mechanical means without defacing the blade.

Having now fully described my design what I claim as new and desire to secure by Letters Patent, is:-

The within described ornamental design or trade mark the same comprising the head of Washington impressed on, or in, the sword blade as described.

Witnesses.
